Leicester, England, assignors to United Shoe
Machinery Corporation, Borough of Flemington,
N. J., a corporation of New Jersey

Application November 21, 1939, Serial No. 305,530
In Great Britain December 8, 1938

20 Claims. (Cl. 12—27)

This invention relates to sole fitting machines and is herein illustrated as embodied in a channeling machine.

After channels have been cut in insoles, for example, the channel lips are raised to facilitate the subsequent sewing operation by which uppers are attached to the insoles. To eliminate the tendency of the raised channel lips to return to their original position, it is customary to make transverse slashes either in the inner channel lip or in both the inner and outer lips. Heretofore, it has been customary to make the slashes in the channel lip during each operating cycle of the machine.

It is an object of this invention to provide a lip slashing device which is so arranged that a variable number of operating cycles may take place between successive operations of the slashing knife. By such an arrangement a sufficient number of slashes may be made in the channel lips to reduce appreciably the tendency of the lips to return to their original position, while at the same time the slashes can be spaced far enough apart to prevent their presence from unduly reducing the strength of the lips. In the illustrated machine wherein the channeling knives are reciprocated back and forth during each operating cycle, the lip slashing device consists of a slashing knife which is coupled to the actuating mechanism of the machine by a control mechanism that includes a counting device which can be set to cause the lip slashing knife to be given a downward movement only after a predetermined number of operating cycles.

Since the insole must be more carefully guided while the channeling operation is proceeding around the toe end than while the operation is proceeding around the other parts of the insole, the operator usually reduces the length of the stroke of the channeling knives while channeling around the toe end. This would normally cause the transverse slashes made by the slashing knife to lie appreciably closer together at the toe than in the other parts of the insole which is considered to be undesirable because it unnecessarily weakens the insole lip in that area.

In accordance with another feature of this invention, means are included in the control mechanism for the lip slashing knife which acts automatically when the length of the stroke of the channeling knives is reduced to delay the successive slashing actions of the slashing knife until a greater number of operating cycles have occurred than takes place during the channeling of other parts of the insole where longer knife

strokes are used. As illustrated, this means consists of a supplemental control for the counting device which modifies the setting of that device when the channel knife stroke is shortened.

The term "operating cycle of the machine", as used herein, refers to one of a series of operations which are repeated during the channeling of a work piece such as a sole. For example, in a machine employing oscillating knives such as the one illustrated herein, an operating cycle would be the movement of a channeling knife from the time it starts on a cutting stroke until it is ready to start on the next cutting stroke. In a machine where the channeling knives are stationary and the work is forced past the knives by feeding means, such as an oscillating feed foot, one complete movement of such means would be an operating cycle.

These and other features of the invention including certain details of construction and combination of parts, will be shown as embodied in the illustrated machine and will be pointed out in the appended claims.

Referring to the accompanying drawings,
25 Fig. 1 is a front elevation of the head of a channeling machine embodying this invention;

Fig. 2 is a transverse section in elevation taken through the machine shown in Fig. 1 at a point to the rear of the view shown in that figure, Fig. 30 2, illustrating the control mechanism for the slashing knife;

Fig. 3 is a side elevation taken from the left of the machine as viewed in Fig. 1 showing a portion of the knife carrying mechanism of the illustrated machine;

35 Fig. 4 is an elevational view showing details of the mounting of one of the slashing knives;

Fig. 5 is a plan view, partly in section, of various work engaging devices of the illustrated machine showing their relation to the edge of an insole which is indicated by dot and dash lines, and

40 Fig. 6 is a front elevation of the control mechanism for the slashing knives shown in Fig. 1, with the overlying structure broken away.

The illustrated channeling machine, except as will hereinafter appear, is similar to the machine disclosed in the United States Letters Patent No. 1,023,801, granted April 23, 1912, upon application of F. E. Bertrand. The illustrated machine includes two slashing knives 11 and 13, the slashing knife 11 being positioned (Fig. 1) between a channeling knife 15 and a channel knife presser gage 17 which correspond respectively to the channel knife 70 and the channel knife presser

gage 12 in the above mentioned patent. The slashing knife 13 which slashes the edge channel lip lies to the right and rearwardly of the slashing knife 11, as viewed in Figs. 1 and 5, and to the right of a channeling knife 19 and its associated presser gage 21. The cutting edges of the knives 11 and 13 extend forwardly and rearwardly of the machine as viewed in Fig. 1 and may be horizontal, i. e., parallel to the upper edge of the insole or may be sloped so as to parallel the cuts made by their associated channeling knives, respectively, so that the bottoms of the slashes will be substantially parallel to the bottoms of the channels made by the channeling knives. The rear end of the cutting edge of the slashing knife 11 is spaced from the front end of the slashing knife 13 (Fig. 5), the space between these ends of the knives being such that the knives do not cut into the part of the insole, known as the between substance, which lies between the bottoms of the channels.

The slashing knives are operated to cut into the insole just as the channeling knives and their associated presser gages reach the end of their work feeding movement. The slashing knife 11 is arranged to move to and fro with the channeling knives and makes its cut immediately ahead, in the direction of feed, of the rear-most position of the channel knife 15. However, the slashing knife 13 does not partake of this to and fro movement and is, therefore, spaced a sufficient distance to the right of the presser gage 21 (Fig. 5) so that the latter gage may move to the right with the channeling knives a distance equal to the length of the longest stroke of the channeling knives without coming in contact with the slashing knife 13. With this arrangement, the channeling knife 15 cuts through the slash formed by the slashing knife 11 very soon after the channeling knives begin to move toward the right on their cutting stroke. Due to the location of the slashing knife 13, the channeling knife 19 does not cut through the slash made by the knife 13 until the second cutting movement of the channeling knife 19 after the slashing knife 13 has cut into the insole. By positioning the slashing knife 13 to the rear of the point of operation, as described above, it will cut slashes in the outer lip when a wide margin is being formed, as when the channeling operation is progressing in the shank portion of an insole, but the knife will not make slashes when narrower margins are being formed, as around the toe.

The arrangement whereby the slashing knives are operated at the end of the work feeding movement so that the channeling knife 15 cuts across the slash formed by the slashing knife 11 very soon after the channeling knife commences its cutting movement, causes the inner channel lip of a sharply pointed insole to be satisfactorily slashed at one or more points around the toe end of the lip. The benefits of this arrangement might better be understood by considering the action of the knives if the slashing knife 11 were located farther away from the channeling knife 15. Under these circumstances, the slash cut by the slashing knife 11 would be made farther away from the starting point of the channel cutting stroke and the channel knife 15 would pass across the slash near the end of its normal cutting movement. When the channeling operation reaches the toe and the length of the stroke of the channeling knife is reduced, the slash might be formed so far ahead of the start-

ing point of the channel cutting stroke that, owing to the quick turning of the insole as the channeling operation proceeds around the toe end, the channeling knife might miss the slash entirely.

The slashing knife 13 is secured by a clamp screw 25 to the lower end of a rod 27 (Figs. 1 and 6) which is slidably mounted in bearings 29, 29 on the head of the machine. The rod 27 has secured to it by a screw 31, a block 33. If the screw 31 is slackened the rod 27 may be turned in its bearings so that the cutting edge of the knife 13 lies at any desired angle to the direction of the feed. The block 33 has adjustably secured to it by a screw 35, a bracket 37 which is connected to the slashing knife 11. The screw 35 passes through a vertical slot 39 in the bracket 37 so that the bracket may be adjusted vertically on the block 33. The bracket 37 has formed in it a recess 41 which receives a roll 43 carried by the upper end of a bar 45 to the lower end of which is secured, by a screw 47, the slashing knife 11. The bar 45 is slidably mounted in a channel knife carrier 49 which in turn has secured to it by a screw 51 the channel knife presser gage 17 and the channel knife 15. The channel knife carrier 49 is secured to a bracket 53 formed on a slide 55 (Fig. 3) which is mounted in a swinging carrier 57 (Fig. 1), the carrier 57 being supported by pins 59 mounted on the machine frame and is swung to and fro during the operation of the machine by an eccentric 61 (Fig. 2) on a drive shaft 63. The channel knife carrier 49, bracket 53, and swinging carrier 57 correspond respectively to the members 68, 66 and 34 in the above mentioned patent to Bertrand.

The slashing knife 11 being attached to the rod 45 which is slidably mounted in the channel knife carrier 49, is carried to and fro with the channel knives and the presser gages. However, the slashing knife 13 does not partake of this to and fro movement as it is carried by the rod 27 which is journaled in bearings 29 that are attached to the machine frame. This relative movement between the slashing knives 11 and 13 is permitted by the recess 41 in the bracket 37 which allows the rod 45 and the knife 11 to move relatively to the rod 27 and the knife 13 in a direction laterally of the machine but at the same time causes the slashing knives 11 and 13 to be moved up and down together by a mechanism which will now be described.

The block 33 (Figs. 1 and 6) has formed in it a horizontal recess 65 in which is slidably mounted a block 67 carried by an arm 69 which is secured to a shaft 71. The arm 69 is normally held up by a spring 73 against a stop face 74 (Fig. 3) formed on a vertically adjustable bracket 75 (Fig. 1) secured by a screw 77 which passes through a vertical slot in the bracket 75 to the aforesaid slide 55. When the screw 77 has been slackened the bracket 75 may be adjusted vertically by means of a rotatable stud 79 in the bracket, the stud having an eccentric portion which enters a groove 80 in the slide. The slashing knives rise with the channeling knives and the presser gages by reason of the fact that the arm 69, which controls the vertical movement of the slashing knives, is held against a stop 74 by a spring 73. As will hereinafter appear, the slashing knives are moved downwardly a uniform distance from their raised position and as this position is determined by the stop 74 which is controlled by the presser gages, the knives

will cut into the work the same distance irrespective of the thickness of the work.

By adjusting the bracket 75, the raised position of the slashing knives may be adjusted upwardly or downwardly relatively to the channeling knives and presser gages and, since the downward movement of the slashing knives is uniform, the depth of the cuts made in the work by them may thus be varied. By adjusting the bracket 37 vertically, the slashing knife 11 may be adjusted relatively to the slashing knife 13.

The shaft 71 has secured to it an arm 81 (Fig. 2) having an arcuate face 83 which is concentric to the axis of the shaft. The shaft 71 also has rotatably mounted on it a bell crank lever 85. One arm 87 of the bell crank lever 85 carries a roller 89 and a spring 91 which tends to wedge the roller against the face 83 of the arm 81 and a relatively inclined face 93 of a recess in the arm 87 in which the roller is mounted. The arm 87 of the bell crank lever 85 is normally held up by a spring 95 against an adjustable screw 97 secured in the machine frame. When the arm is in this position an adjustable screw 99 in the machine frame holds the roller 89 away from the faces 83, 93 so that the face 83 on the arm 81 can move past the roller with the channeling knives and the presser gages as they rise and fall in response to variations in thickness of the work. While the heightwise position of the arm 81 will vary with the different thicknesses of the work, its face 83 will at all times be in a position in which it may be engaged by the roller 89.

Another arm 101 of the bell crank lever 85 has pivoted on it at 103 (Fig. 2) a latch 105 which is arranged to be moved into the path of a block 107 on a cam lever 109 which carries a cam roll 111 that engages in a cam groove 112 in a cam on the driving shaft 63. In Fig. 2 the latch is shown in its upper position and when the cam lever 109 is moved to the left from the position shown in Fig. 2 the block 107 will engage the latch 105 and move the bell crank lever 85 about the shaft 71. As soon as the movement of the bell crank lever 85 commences, the face 93 on the arm 87 will engage the roller 89 and press it against the face 83 on the arm 81 so that the arm 81 and shaft 71 will rotate with the arm 87 and cause the arm 65 and the slashing knives to move down into engagement with the work. The latch 105 is normally held below the position shown in Fig. 2 by a spring 113, the latch being moved up into the path of movement of the block 107 by a mechanism which will now be described.

A ratchet member 115 (Fig. 2) having ratchet teeth 117 is rotatably mounted on the shaft 71. The ratchet teeth 117 are engaged by a pawl 119 pivoted on an arm 121 of the aforesaid cam lever 109, the arrangement being such that the ratchet member is moved one step during each cycle of the machine. The ratchet teeth 117 are also engaged by a stop pawl 123 pivoted on a stud 124 attached to the machine frame, the stop pawl normally preventing the return movement of the ratchet member 115. The ratchet member 115 has on it a face 125 which, after a predetermined number of movements of the ratchet member, comes into engagement with a pin 127 slidably mounted in the arm 101. When the pin 127 is forced downwardly by the face 125 its lower end engages the arm 129 on the latch 105 and moves the latch up into the path of movement of the block 107 on the cam lever 109 so

that the next time the cam lever is operated it will rotate the bell crank lever 85 and thereby cause the knives 11 and 13 to slash the work.

When the bell crank lever 85 is rotated to cause the slashing knives 11 and 13 to cut into the work, a screw 131 which is adjustably mounted in a lug 133 on the bell crank lever 85, moves the pawls 119, 123, out of engagement with the ratchet teeth 117 and allows the ratchet member 115 to be returned by the aforesaid spring 113.

The ratchet member 115 has mounted on it an adjustable screw 135 (Fig. 2) which, when the ratchet member is returned by the spring 113, moves into engagement with a pin 137 secured to an arm 139 which is adjustable about the shaft 71. The arm 139 is pivotally connected to a link 141 which is in turn pivotally connected to an arm 143 of a bell crank lever 144 that is rotatably mounted on a shaft 145 which corresponds to the shaft 140 in the above mentioned patent to Bertrand. Another arm 147 of the bell crank lever 144 is pivotally connected to a rod 149 that is in turn connected to the feed length change mechanism and to a treadle lever which controls that mechanism.

The screw 135 (Fig. 2) may be adjusted so that the distance between the pin 137 and the screw is varied with the result that the ratchet member 115 has to move a greater or less distance, according to the adjustment of the screw 137, before the face 125 on the ratchet member engages the pin 127 and the slashing knives are actuated. Thus, by adjustment of the screw 135 the number of feed movements of the work between successive slashing movements of the knives may be varied.

Since soles need more careful guiding while the channeling operation is proceeding around the toe than while it is proceeding around the other parts of the sole, the operator customarily reduces the length of the work feeding strokes of the channeling knives while operating in the toe portion of the sole. This would normally cause the slashes made by the slashing knives to lie appreciably closer together in the toe portion than in other parts of the sole. In the illustrated machine, this bunching of the slashes around the toe is avoided by the control mechanism for the pin 137 which operates in the following manner. When the operator depresses the treadle lever (not shown) which is connected to the rod 149 so as to shorten the movements of the work, the pin 137 is moved in a counterclockwise direction as viewed in Fig. 2 by the arm 143 and link 141. The ratchet member 115 will then have to be moved a greater distance before the screw 135 contacts the pin 137 and consequently, there will have to be a greater number of ratcheting operations before the slashing knives are again depressed.

If it is desired to operate the machine without changing the number of feed movements between successive slashes, the arm 139 and link 141 may be removed and a lug may be provided on the arm 101, the lug being arranged so that it extends into the path of the screw 135. With this construction the number of feeding movements which occur between successive slashes is regulated by adjusting the screw 135 and with this arrangement the slashes around the toe will be closer together than along the sides if the length of the feeding movements are reduced when operating around the toe.

The edge gage 23 (Fig. 5) corresponds to the edge gage 210 in the above mentioned patent to

Bertrand and may be adjusted forwardly and rearwardly of the machine to vary the position of the channels with respect to the edge of an insole. Preferably, the gage 23 and the usual beveling knife (not shown) do not move to and fro laterally of the machine with the channeling knives and gages during their feeding and return movements, as is the case in the machine disclosed in the Bertrand patent. To this end, the vertical pin referred to as 224 in the Bertrand patent is removed and the auxiliary slide 218 is secured to the in and out slide 212 so that the edge gage and beveling knife can be adjusted forwardly and rearwardly but do not move laterally of the machine.

To summarize briefly the operation of my device, the slashing knives 11 and 13 are intermittently depressed to cut transverse slashes in the channel lips formed by the usual channeling knives. As the slashing knives 11 and 13 are caused to cut into the work, the pawls 119 and 123 (Fig. 2) are released from the ratchet teeth 117 and the ratchet member 115 is moved in a counterclockwise direction, as viewed in Fig. 2, by the spring 113 until the screw 135 engages the pin 137. As the machine continues to operate, the ratchet member 115 is again rotated in a clockwise direction by the pawl 119 being moved around a tooth length during each cycle of the machine until the face 125 on the ratchet member 115 engages the pin 127. On the next cycle of the machine the pin 127 is depressed causing the latch 105 to move up into the path of movement of the block 107 on the cam lever 109 so that the slashing knives 11, 13 are again being depressed when the cam lever 109 is next operated. When the length of the feed strokes are shortened as, for example, when the operation progresses around the toe end of a sole, the timing of the slashes will be varied by the adjustment of the pin 137 which is shifted by the treadle that varies the length of the feeding movements.

Having thus described our invention, what we claim as new and desire to secure by Letters Patent of the United States is:

1. A machine for operating upon soles comprising a knife arranged to make cuts in a sole, mechanism for operating said knife periodically in timed relation to the operating cycles of the machine, and means for varying the ratio between the operating cycles of the machine and the operations of said knife.

2. A channeling machine for operating upon soles comprising a channeling knife, a slashing knife arranged to make cuts in the area operated upon by the channeling knife, and actuating mechanism for causing the slashing knife to operate periodically in timed relation to and with a frequency less than that of the operating cycles of the machine.

3. A channeling machine for operating upon soles comprising a channeling knife, a slashing knife arranged to make cuts in the area operated upon by the channeling knife, mechanism for operating the slashing knife in a predetermined relation to the operating cycles of the machine, and adjustable means for regulating the ratio between the operating cycles of the machine and the operations of the slashing knife.

4. A machine for operating upon soles comprising a channeling knife, a slashing knife arranged to make cuts in the area operated upon by the channeling knife, actuating mechanism for the slashing knife including a counting device, means for operating the counting device during each

operating cycle of the machine, and further means rendered operable by the counting device after a predetermined number of said operating cycles for causing the actuating mechanism to force the slashing knife into the work.

5. A channeling machine for operating upon soles comprising a channeling knife, a drive shaft for causing the operation of the channeling knife, a slashing knife arranged to make cuts in the area operated upon by the channeling knife, operating means for said slashing knife including a member which is operated by the drive shaft during each operating cycle of the machine, a control linkage for the slashing knife, and a counting device also operated by the driving means during each operating cycle, said counting device being arranged after a predetermined number of operations to couple said member with the control linkage whereby the slashing knife will be actuated when the member is next operated.

6. A machine for operating upon soles comprising a channeling knife, a drive shaft for operating said channeling knife, a slashing knife arranged to make cuts in the area operated upon by the channeling knife, a member operated by the drive shaft during each cycle of operation of the machine, control linkage for the slashing knife including an arm which is mounted for movement into and out of the path of said member, and a ratchet mechanism controlled by the drive shaft, said ratchet mechanism being arranged to move the aforesaid arm into the path of the movable member after a predetermined number of operating cycles of the machine.

7. A channeling machine for operating upon soles comprising a channeling knife, a slashing knife arranged to make cuts in the area operated upon by the channeling knife, and an actuating mechanism for said slashing knife including a ratchet device for regulating the ratio between the operating cycles of the machine and the operations of the slashing knife.

8. A machine as defined in claim 5 in which adjustable means are arranged in cooperative relationship with the ratchet mechanism for changing the ratio between the operating cycles of the machine and the operations of the slashing knife.

9. A channeling machine for operating upon soles comprising a channeling knife, a slashing knife arranged to make cuts in the area operated upon by the channeling knife, actuating mechanism for the channeling knife including a member which is oscillated during each operating cycle of the machine, control linkage for the slashing knife, said control linkage having an arm movable into the path of movement of the oscillating member, a counting device consisting of a ratchet mechanism which is operated during each operating cycle of the machine, said ratchet mechanism being arranged to move the arm into the path of movement of the oscillating member after a predetermined number of operations whereby the slashing knife will be operated upon the next operation of the oscillating member, and means for releasing the ratchet mechanism when the slashing knife is operated to permit the ratchet mechanism to return to its initial position after each operation of the slashing knife.

10. A channeling machine for operating upon soles comprising a pair of channeling knives, a pair of slashing knives associated with said channeling knives, one of the slashing knives being arranged for movement with the channeling knives and the other slashing knife being arranged for movement in a fixed path, and actuat-

ing mechanism for the slashing knives including adjustable means for regulating the ratio between the operating cycles of the machine and the operations of the channeling knives.

11. A channeling machine for operating upon soles comprising a channeling knife having a feeding movement, a slashing knife, means for communicating the feeding movement of the channeling knife to the slashing knife, and means for moving the slashing knife relatively to the channeling knife to cause the slashing knife to perform a cutting stroke.

12. A channeling machine comprising a channeling knife arranged for movement through a cycle consisting of a cutting stroke and a feeding stroke, a slashing knife arranged for movement with the channeling knife, and means for operating the slashing knife at a point closely adjacent to the starting point of the cutting stroke of the channeling knife.

13. A channeling machine for operating upon soles comprising a pair of channeling knives arranged to cut an inner channel and a marginal channel, and a pair of slashing knives associated with the channeling knives, the slashing knife associated with the inner channeling knife being located closely adjacent to that channeling knife and mounted for movement with it, and the slashing knife associated with the marginal channeling knife being located a substantial distance from that channeling knife in the direction of the feed.

14. A channeling machine for operating upon soles comprising a channeling knife, work feeding means arranged to move a sole through the machine by a succession of feeding movements, a slashing knife arranged to make cuts in the area operated upon by the channeling knife, and means associated with the work feeding means for varying the ratio between the machine cycles and the operations of the slashing knife when the length of the feed movements are varied.

15. A channeling machine for operating upon soles comprising an oscillatable channeling knife, means for varying the length of the feeding stroke of the channeling knife, a slashing knife arranged to make cuts in the area operated upon by the channeling knife, operating mechanism for the slashing knife including adjustable means for regulating the ratio between the operating cycles of the machine and the operations of the slashing knife, and control means for said adjustable means arranged to vary said ratio when the length of the feed stroke of the channeling knife is varied.

16. A channeling machine for operating upon soles comprising an oscillatable channeling knife, a slashing knife arranged to make cuts in the area operated upon by the channeling knife, actuating mechanism for the slashing knife, including a pawl and ratchet device for regulating the ratio between the operating cycles of the machine and the operations of the slashing knife, and means for varying the length of the feeding movements of the sole, said last-named means being arranged to vary the adjustment of the ratchet when the length of the said movement is varied.

17. A channeling machine for operating upon soles comprising a channeling knife, a slashing knife arranged to make cuts in the area operated

upon by the channeling knife, actuating mechanism for the slashing knife including a ratchet device for regulating the ratio between the operating cycles of the machine and the operations of the slashing knife, means for releasing the setting of the ratchet device each time the slashing knife is operated, means for varying the length of the feeding movement of the sole, and a stop controlled by the last-named means for regulating the adjustment of the ratchet device after it has been released.

18. A channeling machine for operating upon soles comprising a channeling knife, a slashing knife arranged to make cuts in the area operated upon by the channeling knife, actuating mechanism for the slashing knife including a ratchet mechanism which is arranged to call the slashing knife into operation after a predetermined number of operating cycles of the machine, said ratchet mechanism being released when the slashing knife is operated, means for varying the length of the feeding stroke of the channeling knife, and a stop controlled by the last-named means for regulating the adjustment of the ratchet mechanism after it has been released, said stop being positioned farther away from its associated part of the ratchet when the feeding stroke of the channeling knife has been shortened thereby to increase the number of machine operations between the successive operations of the slashing knife.

19. A channeling machine for operating upon shoe soles comprising a channeling knife, a slashing knife arranged to make cuts in the area operated upon by the channeling knife, actuating mechanism for the machine including a cam, a lever associated with the cam and operated during each machine cycle, control linkage for the slashing knife including an arm which is arranged for movement into and out of the path of said lever, a pawl and ratchet counter operated by the actuating mechanism for the machine during each machine cycle, said counter being arranged to move the arm into the path of the lever after a predetermined number of operations thereby causing the operation of the slashing knife, means for releasing the pawl and ratchet counter when the slashing knife is operated, an adjustable stop for determining the new setting of the counter, and control means for determining the length of the work feeding movement of the channeling knife, said control means being arranged to vary the setting of the stop when the length of the work feed movement is varied thereby to change the ratio between the machine cycles and the operations of the slashing knife.

20. A machine for operating upon soles comprising a support for a sole, a channeling knife, means for effecting relative movement between a sole on said support and said knife to cause a channel to be cut in the sole, a slashing knife arranged to make cuts in the area operated upon by the channeling knife, an actuating mechanism for causing the slashing knife to operate periodically in timed relation to said means for effecting relative feeding movement, and means for regulating the periodicity of movement of the slashing knife relatively to said means for effecting relative feeding movement.

CERTIFICATE OF CORRECTION.

Patent No. 2,242,415.

May 20, 1941.

WILLIAM NEIL BRAY, ET AL.

It is hereby certified that error appears in the printed specification of the above numbered patent requiring correction as follows: Page 4, second column, line 43, claim 8, for the claim reference numeral "5" read --7--; and that the said Letters Patent should be read with this correction therein that the same may conform to the record of the case in the Patent Office.

Signed and sealed this 24th day of June, A. D. 1941.

Henry Van Arsdale,
Acting Commissioner of Patents.
